UNITED STATES PATENT OFFICE.

DANIEL SCHNEIDER, OF SPOKANE, WASHINGTON, ASSIGNOR, BY MESNE ASSIGNMENTS, TO THE MODERN THRESHING CYLINDER COMPANY, OF SPOKANE, WASHINGTON, A CORPORATION.

ELECTRIC SWITCH.

1,212,567.

Specification of Letters Patent. Patented Jan. 16, 1917.

Application filed April 1, 1916. Serial No. 88,278.

To all whom it may concern:

Be it known that I, DANIEL SCHNEIDER, a citizen of the United States, residing at Spokane, in the county of Spokane and State 5 of Washington, have invented a new and useful Electric Switch, of which the following is a specification.

My invention relates to improvements in circuit switches and has for its principal 10 object to construct a switch to be used in connection with radiators wherein steam is generated by heating water with electric resistance heating elements and to so construct the switch that the flow of electricity 15 will be cut off from said heating elements when the pressure of the generated steam reaches a predetermined height and to cause the electricity to flow again when the steam pressure lowers below the predetermined 20 height.

Another object is to provide a switch which may be interposed in an electric circuit which is adapted to heat a resistance element for generating steam so that the 25 switch may regulate the steam pressure and to so construct the switch that it may be adjusted to make and break the circuit at the arrival of any predetermined height of steam pressure.

Another object is to construct a switch of the class described which will be dependable and yet simple in construction and cheap of 30 manufacture.

Still further objects will be described and 35 pointed out in connection with following specification and appended claims.

In the drawings:—Figure 1 shows my switch attached to a steam radiator. Fig. 2 is an enlarged front elevation of the 40 switch. Fig. 3 is a side elevation of Fig. 2 looking in the direction of arrow 3. Fig. 4 is a section on line 4—4 of Fig. 3. Fig. 5 is an elevation of the movable contact member looking in the direction of arrow 5 in 45 Fig. 2.

Like numerals of reference refer to the same parts throughout the various figures of the drawings.

In Fig. 1 I have shown the switch attached to my improved steam radiator fully 50 described in my Patent Number 1,141,888 on

an improved portable electrically-heated radiator of June 1, 1915, but it is understood that I do not limit the use of my switch thereto.

55

A water reservoir is indicated at 1 and resistance heating coils or elements 2 and 3 pass through the reservoir 1 to heat the water contained therein. The steam generated by coils 2 and 3 is conveyed through 60 pipes 4 to radiator 5. A plug 6 is threaded in the radiator 5 as shown in Fig. 2 and a Bourdon tube 7 is secured to plug 6 so that steam may pass through the aperture 8 in plug 6 to the bore or cavity 9 which runs 65 the length of tube 7 as far as the cap 10 which closes the extremity of tube 7.

A depending support 11 is attached to an extension of the plug 6 at 12 and pivotally mounted at 13 on support 11 is the lever 14. 70 A link 15 is pivotally connected at 16 to the cap 10 and is pivotally connected at 17 to the upper extremity of lever 14. At the lower end of lever 14 is provided an internally threaded bore 18 within which is 75 threaded an adjustment screw 19 carrying the knurled head 20. A hook member 21 is pivoted to the screw 19 at 22 and a projection 23 is adapted to be hooked into a flange 24 which is attached at 25 to a leaf or movable member 26. Member 26 is hinged at 27 to a member 28 which is held stationary by such means, for instance, as a bracket 29 secured to member 28 at 30 and clamped to pipe 4 at 31. The movable member 26 carries a metallic depending member 32 secured thereto by bolt and nut means as shown at 33 and is insulated therefrom by a washer 34 made of non-conducting material. A projection 35 of depending member 32 serves as 80 a movable contact member.

A binding post 36 serves to allow a connection for wire 37 which is attached to the coil 2 at 38. The stationary member 28 carries metallic forks 39 and 40 by means of 85 bolts 41 and 42 and the forks 39 and 40 are insulated from each other and from the member 28 by the washers 43 and 44 which are constructed of non-conducting material. The fork 39 is apertured at 45 to receive one 90 pole of the attachment plug 46 from which a wire 47 leads to the source of electricity 48.

A binding post 49 mounted on fork 39 serves as a connection for wire 50 which is attached at its other extremity to coil 3 at 51.

The fork 40 is apertured as at 52 to receive the other pole 53 of the attachment plug 46 and pole 53 is connected to the source of electricity 48 by wire 54. Contact member 35 is so positioned that it will normally contact with or engage the fork 40 since the natural spring of tube 7 will force lever 14 in a clockwise direction and hence push member 26 to the left in Fig. 2.

Suppose now that attachment plug 46 be placed in the position of Figs. 1 and 2, current will flow from the source of electricity 48 through wire 54, pole 53, fork 52, contact 35, member 34, binding post 36, wire 37, coil 2, conductor 55 which connects coils 2 and 3, coil 3, wire 50, binding post 49, fork 39, then out through the remaining pole of the attachment plug 46, through wire 47 back to the source of electricity 48. The water contained in reservoir 1 will be converted to steam by the heat set up in resistance coils or elements 2 and 3 due to the passage of electricity therethrough, and the steam will rise through pipes 4 to radiator 5 and will pass through aperture 8 to the bore 9 of the Bourdon tube 7. As the steam pressure rises the tube 7 will tend to straighten out which will, through the medium of link 15, swing lever 14 in a counter-clockwise direction, thus drawing screw 19, hook members 21 and members 26 to the right in Fig. 2 which will withdraw the contact 35 from engagement with the fork 40 and thus interrupt the path and flow of electricity from the source 18 to the elements 2 and 3. As the steam pressure in radiator 5 and consequently in tube 7 lowers, the tube 7 will, due to its natural spring or resiliency, return to its normal position as shown in Figs. 1 and 2, once more allowing contact 35 and fork 40 to engage thus permitting electricity to again flow through coils 2 and 3.

By disengaging projection 23 from flange 24 it will be seen that screw 19 may be revolved so as to carry member 21 to the right or left with respect to the bore 18. Supposing screw 19 were to be revolved so as to project member 21 farther to the left than is shown in Fig. 2 and projection 23 once more hooked to flange 24, it will be seen that tube 7 will resist this action due to the natural curve of tube 7 and hence contact 35 will be forced with added pressure against fork 40 and it will take a higher steam pressure in radiator 5 and bore 9 to straighten tube 7 sufficiently to disengage contact 35 and fork 40. Thus, it is possible to regulate the position of screw 19 so as to require the steam pressure to reach any reasonable predetermined height before the flow of electricity is cut off from the coils 2 and 3.

65 While I have herein shown and described

one specific embodiment of my invention I do not wish to be limited thereto except for such limitations as the claims may import.

What I claim is:—

1. In a device of the character described, a source of electricity, an electric circuit, a Bourdon tube, means adapted to admit gas to the interior of said tube, means adapted to normally hold said circuit closed, means adapted to automatically open said circuit at a predetermined pressure of said gas, said means comprising a closed extremity provided on said tube, a switch interposed in said circuit and comprising a stationary contact member, a movable contact member, and means adapted to adjustably connect said closed extremity and said movable member. 70 75

15 20 25 30 35 40 45 50 55 60 65 70 75 80 85 90 95 100

2. In a device of the character described, a source of electricity, an electric circuit, a Bourdon tube, means adapted to admit gas to the interior of said tube, means adapted to normally hold said circuit closed, means adapted to automatically open said circuit at a predetermined pressure of said gas, said means comprising a closed extremity provided on said tube, a switch interposed in said circuit and comprising a stationary contact member, a movable contact member, means adapted to adjustably connect said closed extremity and said movable member, and means for adjusting said means for automatically breaking said circuit to allow said last mentioned means to actuate at different predetermined pressures of said gas. 100

20 25 30 35 40 45 50 55 60 65 70 75 80 85 90 95 100 105 110 115 120 125

3. In an electric switch, a stationary contact member, a movable contact member hinged to said stationary member, a unitary means normally holding said movable member in contact with said stationary member and adapted to withdraw said movable member from contact with said stationary member at a predetermined time, said means comprising a Bourdon tube, a lever, a link connecting one extremity of said tube to one extremity of said lever, and hook means connecting said lever and said movable contact member.

4. In an electric switch, a resilient curved hollow tube, means adapted to admit gas to said tube, a closed terminal provided on said tube, a link pivotally connected with said closed terminal, a stationary contact member, a movable contact member hinged to said stationary member and normally held by the resiliency of said tube in contact with said stationary member, a pivotally supported lever connected to said link, and hook means connecting said lever and said movable contact member. 115 120 125

5. In an electric switch, a resilient curved hollow tube, means adapted to admit gas to said tube, a closed terminal provided on said tube, a link pivotally connected with said closed terminal, a stationary contact 130

member, a movable contact member hinged to said stationary member and normally held by the resiliency of said tube in contact with said stationary member, a pivotally supporting lever connected to said link, an adjustment screw threadably mounted on said lever, and a hook member pivoted to said adjustment screw and movably attached to said hinged supporting arm.

10 6. In an electric switch, a stationary contact carrying member, fork members mounted on said stationary member and insulated one from the other and from said stationary member, a supporting arm hinged to said stationary member, a second contact member mounted on said supporting arm and normally contacting with the other of said fork members, an insulating member positioned between said second contact member and said arm, a binding post provided on said second contact member, a 15 Bourdon tube, one terminal of said tube being closed and the other terminal of said tube being open, a link pivotally connected with said closed terminal, a pivotally mounted lever, said lever being pivotally connected to said link, an adjustment screw threadably mounted on said lever, and a hook member pivoted to said adjustment screw and movably attached to said hinged supporting arm.

20

25

7. In an electric switch, a stationary contact carrying member, fork members mounted on said stationary member and insulated one from the other and from said stationary member, a binding post provided on one of said fork members, a supporting arm hinged to said stationary member, a second contact member mounted on said supporting arm and normally contacting with the other of said fork members, an insulating member positioned between said second contact member and said arm, a binding post provided on said second contact member, a 20 Bourdon tube, one terminal of said tube being closed, a link pivotally connected with said closed terminal, a pivotally mounted lever, said lever being pivotally connected to said link, an adjustment screw threadably mounted on said lever, and a hook member pivoted to said hinged supporting arm. 25

In testimony whereof I hereby affix my signature in the presence of two witnesses.

DANIEL SCHNEIDER.
